UNITED STATES PATENT OFFICE.

HOWARD B. JONES, OF CHICAGO, ILLINOIS, ASSIGNOR TO ROTARY MANUFACTURING CO., OF CHICAGO, ILLINOIS, A CORPORATION OF ILLINOIS.

PUMP.

Application filed February 27, 1922. Serial No. 539,374.

To all whom it may concern:

Be it known that I, HOWARD B. JONES, a citizen of the United States, residing at Chicago, in the county of Cook and State of Illinois, have invented certain new and useful Improvements in Pumps, of which the following is a specification.

This invention relates to pumps, and refers more particularly to an air pump which is adapted for use on motor cars and the like, although in its broader aspects the invention is adapted for a wide variety of uses.

An exemplification of my invention in a preferred form is illustrated in the accompanying drawings in the manner following:

Figure 1 is a side elevation of the pump;

Figs. 2 and 3 are elevations looking, respectively, toward the front and rear ends thereof;

Figs. 4, 5, and 6 are sectional views taken, respectively, on lines 4—4 of Fig. 3, 5—5 of Fig. 1, and 6—6 of Fig. 1; and

Fig. 7 is a detail in section taken on line 7—7 of Fig. 5.

It may be stated by way of introduction that the present pump embodies many of the features set forth in an application of Charles A. Anderson heretofore filed October 16, 1919, as Serial No. 331,075, and is designed to be mounted in operative relation with any suitable driving element, such as the fan belt of an automobile. The present pump comprises two principal elements A and B, the former of which may be termed the rotor and the latter the stator. The rotor is circular in form so as to provide an outer periphery 10 adapted for engagement by a driving element to impart rotation thereto. At the front side of the rotor element, i. e., the side which is proximate to the operator, the body of the rotor is closed by a transverse wall 11 from which is extended a hub 12 providing a bearing for an eccentric 13. Extending forwardly from the hub is a shaft 14 rotatably mounted in a sleeve which is fixedly carried by the stator element B. The eccentric is removably carried by the stator as through the medium of screws 16 (see Figs. 5 and 6), and the stator in turn is held in place as by means of a bolt 17 screwed into the shaft end, the bolt head 18 bearing against a washer 19 which overlies the ends of the sleeve and stator body.

According to the construction described, the

rotor element may be revolved freely within the body of the stator to which the eccentric 13 is fixedly connected.

The body of the rotor is formed with two cylinders 20 and 20' in which are mounted for alternate reciprocation pistons 21 and 21' so as to provide a multiple pump. Each cylinder is open at its rear end, and at its forward end communicates through a passage 22 formed longitudinally in the shaft with a lateral passage 23. The parts just described are duplicated for each cylinder and similar reference numerals modified only by the addition of a "1" are applied to the second set thereof. The two passages 23 open upon opposite sides of the shaft and surrounding sleeve one registering with an outlet nipple 24 when the other is in communication with a port 25 which opens to the atmosphere. From the preceding description it will be observed that with each inward stroke of the two pistons compressed air from one will be forced through the associated shaft passage to be delivered through the nipple to a hose or pipe connection (not shown).

Each piston is fitted tightly within its associated cylinder with the aid of suitable packing, such as a leather gasket 30. Upon the rear side of each piston is mounted a plate 31 which carries a pair of ears 32 between which extends a pin 33 providing a pivotal connection with an arm 34 that is fixed to a rock shaft 35 mounted within suitable bearings 36 that are provided on the rear side of the rotor body. By reference to Fig. 3 it will be noted that the two cylinders wherein the pistons are mounted to reciprocate are arranged upon diametrically opposite sides of the circular body of the rotor, and that the two rock shafts 35 are situated upon opposite sides of the two cylinders in substantial parallelism with a line extending between their axes, thus providing a very compact arrangement. Through the transverse wall of the rotor are two openings 36^a through each of which extends a second arm 37 which is fixedly carried by each rock shaft. The forward end of each of these latter arms is connected as by a pivot pin 38 to a head 39, two of these elements being projected laterally from an elongated ring plate 40 which is in the general formation of an oval or ellipse. Arranged to engage with the interior periphery of the ring plate are

antifriction members 41 in the form of balls carried within a suitable retainer which is mounted upon the outer periphery of the eccentric 13.

5 The construction just described is such that relative movement between the stator and rotor will result in the eccentric reciprocating the ring plate with a consequent movement of the two arms 37 which rock the 10 shafts 35 and arms 34 to alternately reciprocate the two pistons 21 and 21'. When compression takes place in the cylinder 20 the air forced therefrom is discharged through the passage 22 and outlet nipple 24, and simultaneously there is a registration of the 15 port 25 with the other transverse passage 23' permitting air to enter the associated cylinder 20' during the suction stroke of its piston. When the stator has been turned 20 another 180° relative to the rotor, this relationship will be entirely reversed with the port 25 in communication with the other cylinder 20 wherein a suction is now taking place, the cylinder 21' meanwhile discharging 25 its compressed air through the outlet nipple.

Associated with the parts hereinbefore described are lubricating elements 45 and 46 in the form of a reservoir adapted to hold oil 30 which may be fed by wicks 47 to the revolving surfaces of the shaft 14 and sleeve 15. Additionally a spiral groove 48 may be provided in the shaft periphery to better distribute the oil over its bearing surface.

35 Among the advantages derivable from my invention are the compact and efficient relationing of the operating parts. By using duplex piston mechanisms, I am enabled to build up an air pressure in a very short 40 space of time without requiring any appreciably greater power for the operation thereof. In designing a pump of this character, the several parts have been so related to each other and to the rotor and stator bodies as 45 not to add greatly to the expense of their manufacture and to the size of the apparatus. For these reasons it may be conveniently applied in place and operated.

50 It is apparent to those skilled in the art that the details of construction may be varied without in any way departing from the spirit or scope of the invention as set forth in the appended claims.

I claim:

55 1. In a pump, the combination of rotor and stator elements in the former of which are a pair of cylinders, a piston in each cylinder, and means for reciprocating the two pistons comprising two rock shafts one 60 connected with each piston, a single reciprocating member connected to both rock shafts, and an eccentric carried fast by the stator and adapted to reciprocate the member, substantially as described.

65 2. In a pump, the combination of rotor

and stator elements, the former having a circular body in which are formed two cylinders each having its axis parallel with the axis of the rotor and arranged diametrically on opposite sides thereof, a piston in each cylinder, and means for operating the two pistons comprising an eccentric carried fast by the stator, and connections from the eccentric to each piston adapted to operate the same in alternation, substantially as described.

3. In a pump, the combination of rotor and stator elements, the former having a circular body in which are provided two cylinders each having its axis parallel with the rotor axis and aligned diametrically on opposite sides thereof, a piston in each cylinder, and means for alternately operating each piston comprising in each instance a rock shaft mounted on the rotor to one side of the two cylinders, a connection in each instance between the shaft and one piston, a reciprocable member connected with both rock shafts, and an eccentric carried by the stator adapted to move the reciprocable member to thereby rock both shafts, substantially as described.

4. In a pump, the combination of rotor and stator elements, the former having a circular body open at its rear end and closed at its forward end, a shaft extending outwardly from the closed end of the rotor body, on which shaft the stator is mounted for relative rotation, there being formed in the rotor a pair of cylinders each of which communicates with a passage extending lengthwise of the rotor shaft and thence laterally to opposite sides thereof, there being a pair of openings in the stator body adapted to register simultaneously with the lateral passages in the rotor shaft when the parts are in a predetermined position of adjustment, a piston in each cylinder, and means connected with the stator adapted to alternately reciprocate the two pistons whereby air compressed by one is forced outwardly through one of the shaft passages simultaneously with admission of air through the other shaft passage in response to the suction stroke of the other piston, substantially as described.

5. In a pump, the combination of rotor and stator elements, the former having a shaft extending through the latter, duplex piston mechanisms in the rotor, an eccentric on the stator, and connections between the two piston mechanisms and the eccentric comprising two sets of elements and one common element adapted to be engaged by the eccentric, substantially as described.

6. In a pump, the combination of a rotor and stator, the former containing duplex piston mechanisms on diametrically opposite sides of its axis, a shaft extending from the rotor through the stator, means for re-

movably mounting the stator upon the rotor shaft, an eccentric removably secured to the stator, an element engaged by the eccentric adapted to be reciprocated thereby, and connections from said element one to each of the piston mechanisms adapted to reciprocate the same in alternation, there being passages leading from each mechanism through the rotor shaft, and other passages in the stator communicating therewith only ¹⁰ when the rotor and stator are in predetermined relative positions, substantially as described.

HOWARD B. JONES.
